US0D1072735S

(12) **United States Design Patent** (10) **Patent No.:** **US D1,072,735 S**
Xu (45) **Date of Patent:** **** Apr. 29, 2025**

(54) **ENERGY STORAGE AND POWER SUPPLY DEVICE**

(71) Applicant: **VIGORPOOL, INC.**, Flushing, NY (US)

(72) Inventor: **Zhichao Xu**, Flushing, NY (US)

(73) Assignee: **Vigorpool, Inc.**, Flushing, NY (US)

(**) Term: **15 Years**

(21) Appl. No.: **29/808,437**

(22) Filed: **Sep. 20, 2021**

(51) LOC (15) Cl. **13-02**

(52) U.S. Cl. **USPC D13/110**
